UNITED STATES PATENT OFFICE.

GEORGE E. AUSTIN, OF NEW YORK, AND FREDERICK LACHANCE, OF BROOKLYN, NEW YORK, SAID LACHANCE ASSIGNOR TO SAID AUSTIN.

PINION-PULLER.

1,150,729.

Specification of Letters Patent.

Patented Aug. 17, 1915.

Application filed August 15, 1914. Serial No. 856,962.

To all whom it may concern:

Be it known that we, GEORGE E. AUSTIN and FREDERICK LACHANCE, citizens of the United States, residing respectively, at New York and Brooklyn, in the counties of New York and Kings, respectively, and State of New York, have invented certain new and useful Improvements in Pinion-Pullers; and we do hereby declare the following to be a full, clear, and exact description of the invention, such as will enable others skilled in the art to which it appertains to make and use the same.

This invention relates to repairing apparatus and has for an object to provide a means for removing the pinions from motor shafts or the like.

A further object of this invention is a provision of means for positively engaging a pinion or the like and means for engaging the end of the support for said pinion or the like, one of said means having movement with respect to the other.

A further object of this invention is the provision of means for gripping a pinion or the like which has been placed in proximity to a housing or bearing.

A further object of this invention is a provision of means for transmitting a great pressure against the supporting medium for a pinion or the like which pinion or the like is held by a portion of this apparatus.

A further object of this invention is a provision of means for producing the desired adjustment of the apparatus.

Further objects will be apparent from the following specification appended claims and drawings, in which,

Figure 1 is a side elevation of a device constructed in accordance with this invention, Fig. 2 is a plan view thereof, Fig. 3 is a horizontal sectional view, Fig. 4 is an elevation of the pinion gripping means, and Fig. 5 is a vertical sectional view through an apparatus constructed in accordance with this invention.

In repairing motors or the like, it is frequently desired to remove the pinions from the shafting and as the pinions are bound so securely to the shafts it is necessary that great strain be exerted in starting the movement of the pinion on the shaft. Also, in the compact design of some motors, it is difficult to get a gripping means about a pinion as the housing for the motor or bear-

ing is disposed so close to the end of the pinion.

In this invention there is a base 10 from which rises a standard 11 which is provided with the usual flanges 12 and this standard is slotted as at 13 to receive a pin 14 for clamping the head 15 to said standard. The base is also provided with the threaded socket 16 in which is disposed the threaded end of the stem 17 and this stem has a hand-wheel 18 secured thereto. The head 15 is provided with a socket 19 to receive the upper end of the stem 17.

The head 15 is provided with a central bore 20 in which operates a ram 21 which is threaded through a portion of its length as at 22 for engagement in a block 23. A hand-wheel 24 is secured to the end of the ram as shown.

The head 15 is provided with ears 25 in which are secured trunnions 26 and upon these trunnions are mounted the sleeves 27 which have the periphery thereof formed in cams to receive the ends of links 28 which links are connected at their opposite ends 29 carried by the block 23. The sleeves 27 are further provided with flanges 30 from which extend ears 31 to which the curved ends of a handle 32 are secured. It is obvious that as the handle 32 is swung the sleeves 27 are rotated about the trunnions 26 and the relative distance between the block 23 and trunnions 26 is varied. The bearing surfaces between the trunnions 26, sleeve 27 and links 28 are provided with roller bearings or any other anti-friction means.

The forward end of the head 15 is provided with laterally extending ears 33 between which are pivoted the parallel shank 95 members 34 which carry jaw members 35, at the ends thereof. The ears 33 are slotted as at 36 to permit adjustment of the shanks 34 and to assist in returning the shanks to spaced position, coiled springs 37 in compression are placed between the shanks and the head 15 as shown.

The jaw members 35 have a sliding movement in the frame 38 to produce stability of said jaw members when they are brought in engagement with the pinion and to permit said jaw members to engage the end of a pinion in limited quarters, the jaw members are recessed as at 39 to present a gripping edge 40 near the outer edge of said jaw 110

members. To move the adjustable jaw members into engagement with a pinion when said pinion has been passed between the jaw members a screw 41 passes through one 5 of the end members of the frame 38 and engages the outside of the movable jaw member so that by continued rotation of said screw as by the hand-wheel 42, the desired binding action is produced. To assist 10 in holding the shank members 34 parallel when the jaw members have been clamped securely against the pinion, screws 43 are provided which screws pass through the inner ends of the shank members and engage 15 the side walls of the head 15.

The operation of this device may be summarized as follows: A shaft or the like supporting a pinion to be removed is positioned between the jaws 35 and the jaws 35 are 20 brought into engagement with the end of the pinion so as to exert a binding action on said pinion in its removal. This binding action is produced by the manipulation of the screws 41 and 43. Then the handle 32 25 is raised to increase the distance between the trunnions 26 and block 23 when the screw 22 is rotated to force the ram 21 against the shaft which supports the pinion. Then the handle 32 is swung so that the cams of 30 the sleeves 27 decrease the distance between the trunnions and block 23 and thereby force a movement of the pinion with respect to the shaft which supports it.

Modification may be made within the 35 scope of the claims and the drawings submitted herewith are for illustrative purposes only.

Having thus described our invention, we 40 claim:

1. In a device of the class described in combination with a ram, a supporting sleeve

for said ram, jaw members having a gripping edge disposed adjacent the outer faces thereof, a frame for said jaw members to lock said jaws in adjusted position, parallel 45 shanks supporting said jaw members, said shanks being adjustably carried by said supporting sleeve, means for normally returning said parallel shanks to spaced relation, and further means for locking said parallel 50 shanks against movement.

2. In a pinion pulling device of the class described, a base, a head movably carried thereby, a ram slidably carried in said head, slotted ears formed on said head, shanks 55 slidably mounted in said ears, said shanks having parallel movement with respect to the axis of said ram, jaws formed on said shanks, a frame carried by said jaws to maintain the relative positions of said jaws 60 and means carried by said frame for binding said jaws against the pinion.

3. In a pinion pulling device of the class described, a base, a head adjustably carried thereby, a ram slidable in said head, ears 65 formed on said head, shanks slidably between said ears, said shanks having parallel movement with respect to the axis of said ram, jaws carried by said shanks, a frame carried by said jaws, a screw carried by said 70 frame for binding said jaws against an article, screws carried by said shanks, to maintain parallel relation of said shanks and means to normally return said shanks and jaws to spaced relation.

In testimony whereof we affix our signatures in presence of two witnesses.

GEO. E. AUSTIN.
FREDERICK LACHANCE.
